PROCESS FOR CRACKING PETROLEUM OIL

Original Filed June 1, 1920 2 Sheets-Sheet 2

UNITED STATES PATENT OFFICE

LESTER KIRSCHBRAUN, OF LEONIA, NEW JERSEY, ASSIGNOR TO UNIVERSAL OIL PRODUCTS COMPANY, OF CHICAGO, ILLINOIS, A CORPORATION OF SOUTH DAKOTA

PROCESS FOR CRACKING PETROLEUM OIL

Application filed June 1, 1920, Serial No. 385,463. Renewed May 28, 1928.

This invention relates to improvements in process and apparatus for cracking petroleum oil, and refers more particularly to a continuous process adapted for use in the tube type of apparatus, although not necessarily limited thereto. In processes of this type the oil may first be subjected to a cracking temperature in a closed coil, as for example, 800 feet of two inch pipe, and then 5 passed to an elongated reacting chamber which may take the form of an 80-foot coil of twelve inch pipe. The process is operated under a sufficient heating pressure to produce the desired cracking. Heretofore, much 10 difficulty has been experienced in keeping the outlet ends of the cracking coil and the vapor chamber free from carbon formation on the walls of the tubes, which results in clogging or burning out said tubes. It is 15 desirable to avoid, as far as possible, the vaporization of the oil in the smaller tubes which are seated in the fire zone, as where vapors are formed, carbon is precipitated. It is also desirable to continuously sweep the 20 carbon out of the vapor chamber.

The present invention is designed to accomplish these objects, and in a simple and effective manner. By means of the present invention I also am able to use a lower heat 25 in the cracking coil, which is highly desirable from the standpoint of effective operation.

The essence of the invention consists in carrying the heated oil entirely (or practically so) through the vapor chamber, which 30 is accomplished by extending the two-inch pipe through the bottom of the vapor chamber throughout its length. The oil is then discharged at or near the far end of the vapor chamber, and the residue drawn off from 35 that end of the vapor chamber farthest remote from such discharge point. By this means, I am enabled to at all times provide a liquid body in the vapor chamber, and obviate the danger of the twelve-inch tubes going dry, or the residuum becoming too highly 40 reduced.

I also, more or less, replenish the heat lost by vaporization in the twelve-inch pipe which forms the vapor chamber, through the inter- 45 change of heat from the oil in the two-inch

pipe which passes through the former, thus in part, heating the residue, or partially converted material in the vapor chamber. The process utilizes the heat of the cracking zone more effectively because of the more uniform 55 temperature existing in the vaporizing zone. The oil in the cracking zone, for example, may be heated from 775° to 825° F. As the oil released from the two-inch pipes vaporizes, it consumes heat; but this is partially 60 compensated for by the heat interchange which prevents undue dropping off of the temperature of the oil and vapors in the twelve-inch pipe. The cooling action of the residue on the oil in the two-inch pipe also 65 tends to prevent the oil in the two-inch pipe from getting too hot and vaporizing, thus precipitating carbon and clogging up the small pipe.

In order that the invention may be more 70 clearly understood, I have shown the accompanying drawings in which Fig. 1 is a somewhat diagrammatic plan view, and Fig. 2 is a side elevation of my apparatus.

Referring to the drawings, 1 designates the 75 furnace in which is mounted the cracking coil 2. Oil is delivered to cracking coil 2, connected by means of pump 3 to any suitable source of supply of charging stock. In suitable supports 4 is mounted the vapor or 80 reacting chamber 5, which takes the form of a relatively large coil. The cracking coil 2 is provided with an extension 6, which is, or may be, of the same or similar diameter to the coil 2, and extends through the vapor chamber 5. This extension 6 delivers the oil into the vapor chamber at the far end of the latter at the point 7 after, of course, being cooled by passage through the vapor chamber 5. The vapor chamber is provided 85 with a residue draw-off 8 controlled by valve 9. It also has risers 10 leading to manifold 11, which in turn is connected to an aerial condenser 12. The aerial condenser 12 acts as a reflux condenser. That portion of the 90 vapor which is not condensed in the reflux condenser 12 passes through water condenser 13 into receiver 14. The receiver 14 is provided with liquid draw-off 15 and throttle valve 16. It also has a gas outlet 17 controlled 95 100

by valve 18. If desired, a throttle 19 may be interposed in the coil 2 just before it enters the vapor chamber, and similarly, a throttle valve 20 may be interposed in the extension 5 6, nearer the discharge end of the latter. The use of the valves 19 and 20 will permit differential pressure being maintained on the system.

The following illustrative run may be 10 given: Starting with gas oil of say 32° Baumé gravity from a Kansas field; it may be heated to an oil temperature in the coil 2, of say 800° F. and subjected to a pressure in the coil 2, of 100 pounds. This pressure of 100 15 pounds may be carried through the system, or not, as desired. Following the process in this way, some 60% of the oil may be converted into pressure distillate of say 51° Baumé gravity. The object of the extension 20 6, which forms the salient feature of the invention, both in process and apparatus, has been heretofore set forth and need not be here repeated. It is to be understood that where pressure is maintained on the entire 25 system this can readily be done by controlling the valves 16, 17, and 9, and opening the valves 19 and 20. In addition to the last mentioned valves, a valve 21 may be interposed in the upper end of the aerial condenser just before it reaches the water condenser. This valve 21 will, of course, be 30 wide open when a uniform pressure is maintained on the system.

I claim as my invention:

35 1. A continuous process of cracking hydrocarbon oil, consisting in passing the oil in a relatively small stream through a closed conduit in a heating zone wherein it is raised to a cracking temperature, in delivering the 40 heated oil constituents into an enlarged reacting chamber, in maintaining a substantially uniform temperature throughout the entire body of oil in said enlarged reacting chamber, by utilizing the heat contained 45 in the heated oil constituents being delivered from the heating zone, by maintaining a heat interchange relationship between such heated oil constituents and the body of oil in said reacting chamber but without permitting 50 said heated oil constituents to come in physical contact with the body of oil in said reacting chamber for a substantial period after its admission thereto and in causing the oil, subsequent to its admission into said reacting 55 chamber, to flow therethrough counter-current to the flow of the heated oil constituents coming directly from the heating zone, and in maintaining a superatmospheric pressure on the oil in the heating zone and 60 reacting chamber.

65 2. A continuous process of cracking hydrocarbon oil, consisting in passing the oil in a relatively small stream through a closed conduit disposed within a heating zone, wherein the oil is raised to a cracking tem-

perature, in passing the heated oil, while in said relatively small stream, throughout substantially the entire length of an enlarged reaction chamber, in then admitting the oil from said relatively small stream to said 70 enlarged reaction chamber, to flow therethrough counter-current to the flow of the oil in said relatively small stream, to maintain the oil undergoing reaction in said enlarged reaction chamber at a substantially uniform 75 temperature, in continuously taking off products of conversion in vaporous form from said enlarged reaction chamber, and in maintaining a superatmospheric pressure on the oil undergoing conversion. 80

3. An improvement in a process for cracking hydrocarbon oil of the character in which the oil is heated in a coil and then transmitted to a reaction zone comprising causing the oil to pass in a confined stream throughout 85 substantially the entire length of the reaction zone in heat interchange relation with oil accumulated in the reaction zone, thence admitting the oil to the reaction zone and during the operation of the process withdrawing residual oil from the reaction zone at a point remote from the point at which 90 the oil is admitted to the reaction zone whereby the oil in said reaction zone flows countercurrent to said confined stream. 95

LESTER KIRSCHBRAUN.
